UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. **7,957**, dated December 29, 1874; application filed December 16, 1874.
[Term of Patent 14 years.]

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

This invention consists in an ornamental design for the casing of a soda-water apparatus to be placed against a wall, the operator standing in front of the apparatus.

In the photograph, A represents the casing of a soda-water apparatus, which is of rectangular form in cross-section. B is the back, which rises vertically from the base, and is provided with an ornamental top, e, this back being intended to be placed against the wall of the apartment, the operator standing in front of the apparatus and between it and the counter. The front plate C has an ornamental top, d, which projects up in front of the portion f, which is inclined from a point on

the inside of the plate C and below the top d to a point, g. Above this inclined portion f is a door, D, which forms the front of the upper part of the apparatus, and is balanced on hinges secured to it on the inner side near its center of gravity, the top of this door being made ornamental, as shown.

What I claim as my invention, and desire to secure by Letters Patent, is—

1. The design for the casing of a soda-water apparatus, substantially as herein shown and described.
2. The design of the balanced door D, substantially as shown and described.
3. The design of the front plate C, having its top d projecting up in front of the inclined portion f, substantially as shown and described.

Witness my hand this 10th day of December, A. D. 1874.

GEO. F. MEACHAM.

In presence of—

P. E. TESCHEMACHER,
G. A. MEACHAM.
